United States Patent Office

Des. 208,666
Patented Sept. 19, 1967

208,666

DUAL STRAIGHTEDGE

Jacque Fresco, 3112 SW. 23rd St.,
Miami, Fla. 33145

Filed Dec. 28, 1966, Ser. No. 5,205

Term of patent 14 years

(Cl. D52—6)

FIG. 1 is a top perspective view of a dual straightedge showing my new design.

FIG. 2 is a bottom perspective view thereof.

FIG. 3 is an end elevation thereof.

I claim:

The ornamental design for a dual straightedge, as shown.
